DESIGN FOR A SHOE

John Henry Schroeder, Portsmouth, Ohio

Application December 12, 1940, Serial No. 97,274

Term of patent 7 years

To all whom it may concern:

Be it known that I, John Henry Schroeder, a citizen of the United States, residing at Portsmouth, in the county of Scioto and State of Ohio, have invented a new, original, and ornamental Design for a Shoe, of which the following is a specification, reference being had to the accompanying drawing, forming a part thereof.

Figure 1 is a side elevational view of a shoe showing my new design.

Figure 2 is a top plan view of the shoe.

Figure 3 is a rear elevational view of the shoe.

My design for a shoe is characterized by a

molded sole and upper of two pieces, these parts being attached by a means of lacing in the manner shown, said lacing extending entirely around the top of the sole engaging in the lower edge of the two parts of the upper; the upper being laced in the back and the lower portion of the vamp, the upper portion containing eyelets for a shoe lacing; and the free edges of the top of the shoe and the toe being scalloped as indicated.

I claim:

The ornamental design for a shoe, substantially as shown and described.

JOHN HENRY SCHROEDER.
